LIFESAVING AND SPORTING FLOAT
DEVICE

Chaim S. Fisch, New York, N. Y.

Application July 11, 1942, Serial No. 450,508

3 Claims. (Cl. 9—21)

This invention relates to new and useful improvements in a life saving and sporting float device.

More specifically, the invention proposes the construction of a float characterized by a central float adapted to be straddled by the legs of a rider and provided at its fore and aft ends with floats arranged in a manner to permit the device to be used for amusement by adults and children at beaches and pools and for more important life saving purposes when disaster overtakes a ship at sea.

Another object of this invention proposes providing the float with a rider's saddle to add to the comfort of the person riding the float in a manner to prevent the tops of the rider's legs from becoming chafed and irritated.

It is a further object of this invention to provide a pair of stirrups suspended from the saddle to receive the rider's feet and guide the movements of the rider's feet in an arcuate path in a manner to propel the float across the surface of the water.

A still further object of the invention proposes providing each of the stirrups with a shoe formed with pivotally mounted fins arranged in a manner to assume an operative extended position when the leg is moved rearward to add to the propelling force of the leg movement and move the float forward at greater rates of speed.

It is another object of this invention to provide a balance bar extended across the central float and formed at its ends with floats arranged in a manner to prevent the central float from tilting sidewise.

It is also an object of this invention to construct a float which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a side elevational view of a life saving and sporting float constructed in accordance with this invention.

Fig. 2 is an enlarged vertical sectional view of a portion of Fig. 1.

Fig. 3 is an enlarged horizontal sectional view taken on the line 3—3 of Fig. 1.

Fig. 4 is a side elevational view similar to Fig. 1, but illustrating a modification of this invention.

Fig. 5 is a perspective view of a float constructed in accordance with a still further modification of this invention.

Fig. 6 is an enlarged partial vertical sectional view of a portion of Fig. 5.

Fig. 7 is an enlarged partial horizontal sectional view taken on the line 7—7 of Fig. 5.

Fig. 8 is a vertical sectional view of the shoes per se.

Fig. 9 is a side elevational view of the float shown in Fig. 5, but with the balance bar pivoted into an inoperative position.

Fig. 10 is a similar view to Fig. 5, constructed in accordance with another modified form of the invention.

The life saving and sporting float, according to this invention, includes a central float 10. The central float 10 is constructed of wood and is materially longer than it is wide so as to be adapted to be straddled by the legs of a rider. This float 10 is constructed of separate sections 11 and 12. The section 12 is formed with an inwardly extended opening 13 into which one end of the section 11 is slidably telescopically engaged. A set screw 14 is threadedly engaged through one wall of the section 12 and bears against the section 11 to hold the sections in various extended positions or completely collapsed. The construction permits the float 10 to be extended to a length desired by the person riding the same.

End floats 15 are mounted fore and aft upon the central float 10. One float 15 is mounted upon the outer end of the section 11 and one is mounted upon the outer end of the section 12. Each float is alike in construction and each comprises an inflatable member 16, preferably constructed of rubber having a central tubular core 17 which engages the end of the float. In the inflated condition of the member 16 the core frictionally engages the float 10 to hold the float securely in position on the float, but when the inflatable member 16 is deflated it is possible to move the floats 15 to desired positions upon the float 10. A valve 18 of conventional construction is mounted upon the inflatable member 16 to permit it to be inflated and deflated when desired. Surrounding each inflatable member 16 there is a cover of protective netting 19 designed to retain the inflatable members 16 in their round shape

when inflated.

The method of using the float is as follows:

The sections 11 and 12 are extended to make the float 10 the desired length and the set screw 14 is tightened to maintain the sections as adjusted. The floats 15 are moved to desired position along the length of the float 10 and inflated through the medium of the valves 18 and the float 10 is then rested upon the surface of the water. A rider then straddles the float 10 and propels himself forward by moving his legs forwards and backwards in the water.

It is believed that it will be readily understood how hours of enjoyment may be derived from the device when used for amusement purposes by adults and children at beaches and pools. The float when provided in numbers aboard a ship could serve equally as well as a life saving device for the passengers in the event disaster should overtake the ship while at sea.

In the form of the invention shown in Fig. 4 the central float 10' is constructed of a single piece of wood and is provided at its center with a rider's saddle 20 of waterproof material. The person straddling the float 10' sits upon the saddle 20 to add to his comfort while using the device and to prevent the tops of his legs from contacting the top corners of the float and be chafed and irritated when the legs are moved forwards and rearwards to propel the float.

The end floats 15' are similar in construction to that previously described, except that the inflatable members 16 are each provided with a downwardly extending lug 21. A length of chain 22 has one link connected to the lug 21 and the other link connected to a loop 23 mounted on the adjacent end of the float 10'.

In other respects this form of the invention is similar to that previously shown and like reference numerals are used to identify like parts in each of the several views.

In the modification shown in Figs. 5 to 9 the construction of the float is similar to that shown in Fig. 4.

This form of the invention is further provided with a pair of downwardly extending stirrups 24. Each stirrup is alike in construction and comprises a length of flexible rubber material 25 formed at its top end with a grommet 26. A pin 27 is engaged through the float 10' slightly in front of the saddle 20 and passes freely through the grommet 26 of the top end of each of the stirrups 24 to pivotally move in an arc about the grommets.

The bottom end of each of the lengths of flexible material 25 continues into a shoe 28 having a stiff sole 29. The bottom face of the sole is formed with a pair of fins 30. These fins 30 are pivotally supported upon the stiff sole 29 of the shoe by means of hinges 31. The hinges 31 are so arranged that when the shoe is moved forwards by the forward movement of the leg upon which the shoe is engaged the fins will pivot into the inoperative horizontal position illustrated by the dot and dash lines 30' in Fig. 8. However, when the leg is moved forward the fins will pivot downwards into the full line vertical position shown in Fig. 8 to assist the leg motion in propelling the float in a forward position.

The form of the invention is also formed with a balance bar 32 arranged to assume a right angular operative position beneath the saddle 20. The bar 32 is constructed of wood and is connected at its center to the float 10' by means of a universal joint 33. The universal joint 33 comprises a socket member 34 having a threaded

shank 35 engaged with the float 10'. A ball member 36 engages the socket member 34 and is attached to the center of the bar 32 by means of a bracket 37 and screws 38. (See Fig. 6.) This universal joint 33 permits the bar 32 to move into any desired position with relation to the float 10' and also permits the bar to be pivoted from an operative position extended at right angles to the float 10' to an inoperative position shown in Fig. 9, extended parallel beneath the float 10'.

The bar 32 consists of two members 32^a and 32^b hinged together at 33^c to permit the folding of the member 32^b adjacent its complementary member 32^a toward the front of the device. In Fig. 5, the dot and dash position 32' shows the two members 32^a and 32^b to be partially swung forward to balance the float device. Either the member 32^a or 32^b may be swung under the float 10, if the user of the device wants to be near another person on another similar device and the full line position of the bar 32 shows the bar members 32^a and 32^b to be turned 180°, or into aligning position which is the maximum angle that may be formed between the members 32^a and 32^b.

The outer ends of the bar 32 is provided with floats 15 which are similar in construction to the floats shown in the first form of the invention.

Hinges 39 pivotally connect the ends of a pair of handles 40 to the bar 32 at points between the float 10' and the floats 15. The free ends of the handles 40 are formed with reduced and shaped gripping portions 41, and when the handles are in the upwardly inclined position shown in Fig. 5 they are adapted to be gripped by the rider to provide a means whereby he may balance himself upon the saddle 20.

In other respects this form of the invention is similar to that previously shown and like reference numerals are used to identify like parts in each of the several views.

In Fig. 10, the soles 29' with fins 30'' are shown to be attached to a person's feet by straps 28' without any stirrup strap, and the saddle 20' is provided with a protecting belt 20^a adapted to engage the waist-line of the person on the device, while a bracing strap 20^b is provided to engage between the protecting belt 20^a and the float 10'. In other respects this form of the invention is similar to the previous form and the various parts may be recognized by similar reference numerals.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A life saving and sporting float, comprising a central float, a rider's saddle mounted on said float, end floats fore and aft of said central float, and means connecting said end floats with the ends of said central float and stirrups pivotally mounted upon the sides of said float to the front of said saddle.

2. A life saving and sporting float, comprising a central float, a rider's saddle mounted on said float, end floats fore and aft of said central float, and means connecting said end floats with the ends of said central float, stirrups pivotally

mounted upon the sides of said float to the front of said saddle, and a shoe mounted on the bottom end of each of said stirrups and each of said shoes being formed with a pair of fins pivotally supported to assume an operative downwardly extended position on the backward movement of the shoe and an inoperative position horizontal to the shoe on the forward movement of the shoe.

3. A life saving and sporting float, comprising a central float, a rider's saddle mounted on said

5 float, end floats fore and aft of said central float, and means connecting said end floats with the ends of said central float and a continuous balance bar, a universal joint connecting an intermediate portion of said balance bar to the bottom of said central float permitting said bar to assume an operative position extended at right angles to said float and an inoperative position parallel to said central float and various angular positions with relation thereto.
